John H. Bunning,
His Attorney.

UNITED STATES PATENT OFFICE.

FRANK C. RODGERS, OF ST. LOUIS, MISSOURI.

DENTAL IMPRESSION TRAY.

Original application filed June 16, 1920, Serial No. 389,384. Divided and this application filed April 17, 1922. Serial No. 554,167.

To all whom it may concern:

Be it known that I, FRANK C. RODGERS, a citizen of the United States, and residing at St. Louis, Missouri, have invented the 5 new and useful Improvement in Dental Impression Trays, of which the following is a specification.

This invention relates to dental impression trays adapted for the purpose of taking 10 impressions of the mouth to reproduce impressions of teeth, gums, palate and adjacent structures. This application is a division of application Serial Number 389,384, filed June 16, 1920.

15 One of the objects of this invention is to provide a dental impression tray, which, while it is constructed to conform generally to the parts to be reproduced, has provisions for preventing the impression material from dropping off of the tray into the 20 mouth or throat, at the same time permitting ready removal of the tray from the impression material and providing ample space for teeth that are out of alinement.

25 Another object of this invention is to provide a dental impression tray having means providing for expansion and contraction of the tray in order to adjust the same to the mouth.

30 Further objects will appear from the detail description taken in connection with the accompanying drawing, in which:

Figure 1 is a plan of an impression tray for the lower jaw;

35 Figure 2 is a side elevation;

Figure 3 is a perspective view;

Figure 4 is a section on the line 4—4, Figure 1, showing the impression material in place; and

40 Figure 5 is a section on the line 5—5, Figure 1.

Referring to the accompanying drawing which shows a tray adapted more particularly to the lower jaw, this tray may be 45 made of sheet or cast aluminum and it comprises a lingual flange 20 and a labial flange 21, which together form an arched trough, a handle 22 being also formed on or attached to the tray body. The termini of the trough have ridges 23 which extend along the sides and bottom thereof to form post-dams for retaining the impression material, but which ridges are shallow so as to not interfere with the placing of the tray

on the teeth. The lingual flange has at its 55 center a notch 24 which permits the legs of the tray to be expanded or contracted by bending.

This lower tray is designed with a curvature that corresponds to the curvature of 60 the lower jaw, the object being to provide a space at the incisal region for sufficient bulk of the impression material so that the same can be distributed equally over the teeth and gums so that it can be readily removed from the curved part of the jaw 65 without breaking into numerous small fragments; it will, therefore, be seen that the bottom of each tray leg is convex, considered in a direction therealong; accordingly the 70 tray will correspond to the curvature of the teeth of the lower jaw as seen in Figures 2 and 3 in order to bring the impression material close to the back teeth.

The inside or lingual flange 20 is designed 75 to extend rootwise below the necks of the teeth to secure an impression below the gum margins; accordingly this flange inclines distally as well as rootwise.

The outside or labial flange is designed 80 to conform to the contour of the gums, being deepest in front with a gradual recession distally, so that this flange extends distally and occlusally. The general rounded angles and curvature more particularly at 85 the ends of the flanges and in the bottom of the trough is, however, such as to permit ready removal of the tray from the impression material and allowing ample space 90 for teeth which may be out of alinement.

The function of the notch 24 at the center of the labial or inside flange 20 is to permit the legs of the tray to be expanded and contracted for the purpose of widening and narrowing the tray so as to conform to 95 the shape of some individual jaws; the provision of this notch, however, not only permits and provides for such adjustment but also prevents distortion of the tray as a whole.

100 It is obvious that various changes may be made in details of construction without departing from the spirit of this invention; It is, therefore, to be understood that this invention is not to be limited to the specific 105 details shown and described.

Having thus described the invention, what is claimed is:

1. A dental impression tray having lingual and labial flanges bounding a distally open arched trough provided with shallow post dams following the transverse curvature of the trough.
  2. A dental impression tray having lingual and labial flanges bounding a trough, said lingual flange being formed to extend beyond said labial flange and rootwise below 10 the necks of the teeth.
  3. A dental impression tray having lingual and labial flanges bounding a trough, said lingual flange being formed to extend beyond said labial flange and rootwise below 15 the necks of the teeth, and said labial flange being formed to follow the gums labially.
  4. A dental impression tray having lingual and labial flanges bounding a trough, said lingual flange extending beyond said 20 labial flange and inclining distally and rootwise.
  5. A dental impression tray having lingual and labial flanges bounding a trough, said lingual flange extending beyond said 25 labial flange and inclining distally and rootwise, and said labial flange inclining distally and occlusially.
  6. A dental impression tray having lingual and labial flanges bounding a distally 30 open arched trough provided with post-dams, said lingual flange extending beyond
- said labial flange and inclining distally and rootwise.
7. A dental impression tray having lingual and labial flanges bounding a distally 35 open arched trough provided with post-dams, said lingual flange extending beyond said labial flange and inclining distally and rootwise, and said labial flange inclining distally and occlusially. 40
  8. A dental impression tray having lingual and labial flanges bounding an arched trough provided with post-dams, the bottom of each tray leg being convex, considered in 45 a direction therealong.
  9. A dental impression tray having lingual and labial flanges bounding a trough, said lingual flange extending beyond said labial flange and inclining distally and rootwise, and the bottom of each tray leg being 50 convex, considered in a direction therealong.
  10. A dental impression tray having lingual and labial flanges bounding a trough, said lingual flange extending beyond said labial flange and inclining distally and rootwise, said labial flange inclining distally and 55 occlusially, and the bottom of each tray leg being convex, considered in a direction therealong.

In testimony whereof I affix my signature this 12th day of July, 1921.

FRANK C. RODGERS.
